UNITED STATES PATENT OFFICE.

JOSHUA J. WORLEY AND WILLIAM J. THOMAS, OF STERRETT, INDIAN TERRITORY.

SHELF-SUPPORTING BRACKET.

No. 845,917.

Specification of Letters Patent.

Patented March 5, 1907.

Application filed July 19, 1906. Serial No. 326,822.

To all whom it may concern:

Be it known that we, JOSHUA J. WORLEY and WILLIAM J. THOMAS, both citizens of the United States, and residents of Sterrett, in 5 the county of Blue, Indian Territory, have invented certain new and useful Improvements in Shelf-Supporting Brackets, of which the following is a specification.

This invention relates to shelf-supporting brackets; and it has for its object to provide a simple and improved bracket device of this class which can be quickly and readily set up in position without permanent attachment to the wall or surface with relation to which 15 it is mounted and without the employment of nails or screws or other permanent securing means, which can be also quickly and readily removed from position in case of emergency or as desired, and which will be 20 conveniently portable.

A further object of the invention is to provide an improved bracket device of the class described which can be constructed entirely of metal; which can be applied under and 25 will be adaptable to various conditions or circumstances of desired use; which in its adjustable and adaptable characteristics will be compact in relation to the space occupied; which will effect economy and other advantages, inasmuch as the bracket device can 30 be set up or removed by simply the adjustable operation of the device itself and without the labor or expense of using permanent securing means, and which will, furthermore, 35 possess advantages in point of convenience, adaptability, adjustability, economy, safety, effectiveness, and general efficiency.

In the drawings, Figure 1 is a front elevation illustrating the improved bracket device in use. Fig. 2 is a side elevation, partly 40 in section, illustrating one of the improved shelf-supporting bracket devices in applied position and showing the adjustable action of the parts in dotted lines. Fig. 3 is a detail perspective view of the top end of the 45 main member or rack-bar of the device.

Corresponding parts in all the figures are denoted by the same reference characters.

Referring to the drawings, 1 designates the 50 main member of the device, which consists of a bar adapted to be placed vertically with relation to the wall or surface, as at 2, in conjunction with which the device is mounted. Said bar 1 is provided at its bottom end 55 with a rearwardly-projecting toe or exten-

sion 3, adapted to engage under the base-board 4 of the wall 2 or between bricks when the bar is applied to an unfinished wall, and at its top end the bar is provided with a rearwardly-projecting extension, as at 5, 60 adapted to bear against the wall 2 and retain the rear edge of the bar a sufficient distance therefrom to enable the sliding operation of the adjustable parts hereinafter described. The top extension 5 is provided with a 65 pointed end, as at 6, which will engage the wall 2 and prevent lateral displacement of the bar when the latter is clamped in operative position. The bar 1 is preferably curved or extended rearwardly, as at 7, a short distance above the toe or extension 3 to form a short projecting portion, the rear edge of which will bear against the wall 2 immediately above the base-board 4 to retain, in conjunction with the top extension 5, the 75 main upper length of the bar a sufficient distance from the wall to enable the operation of the sliding and adjustable parts as above mentioned. The front edge of the bar 1 is provided throughout its length above the 80 curved or rearwardly-projecting portion 7 with serrations, as at 8, forming a rack.

9 designates the adjustable shelf-supporting members of the device, which comprise a body portion, as at 10, carried upon a sleeve 85 or collar 11, which latter embraces and is vertically slidable upon the rack-bar 1. The body portion 10 of the member 9 comprises a normally horizontal top-supporting surface 12 and a serrated edge 14, which is normally 90 vertical and at right angles to the top surface 12 and which has a locking engagement with the serrated front edge 8 of the rack-bar 1, and the body portion 10 is pivotally connected to its carrying sleeve or collar 11 at the 95 vertex of the angle formed by its top surface 12 and edge 14, as shown at 15. The relative construction and arrangement just described results in a locked position of the member 9 at any point to which it has been adjusted, 100 downward pressure upon the body portion 10 of said member 9, caused by weight upon the shelves, only serving to more firmly lock the member in position; but for purposes of adjustment the body portion 10 may be 105 turned upon its pivot to the position shown in dotted lines in Fig. 2 to enable the slidable adjustment or placing of the member 9 at any desired point upon the rack-bar 1.

16 designates a cam-brace device by which 110

the rack-bar 1 may be firmly secured and bound in upright position in engagement with the wall 2. This cam-brace comprises a sleeve or collar 17, embracing and slidably upon the rack-bar 1 above its bearing extension portion 7 and pivotally carrying, as at 18, at its outer end a lever 19. The sleeve or collar 17 carries a pivoted gravity-cam 20, projecting rearwardly toward the rack edge 8 of the bar 1 and having a segmental serrated edge, as at 21, adapted to engage and lock with the serrations 8. The cam 20 is preferably mounted at the pivot 18, which connects the lever 19 and the sleeve 17. The lever 19 carries a pivoted fulcrum-bar 22, which preferably has a pointed lower end 23, adapted to engage the floor 24, the pivot, as at 25, of the fulcrum-bar being at a point intermediate the ends of the lever. The lever 19 is preferably of skeleton construction, comprising two side plates 26 26, between which the fulcrum-bar 22 is received when the cam-brace device 16 is in normal position, and at the lower end of the lever said plates are preferably connected at the outer side of the lever by a cross-piece 27, which will limit the position of the fulcrum-bar 22 when the brace is in normal position and prevent accidental displacement of the fulcrum-bar.

It will be understood that when the rack-bar 1 has been placed in position with the cam 20 engaging the serrated edge 8 and the lever 19 fulcrumed upon the fulcrum-bar 22, with the latter in approximately upright position and engaging the floor 24, (this initial position being illustrated in dotted lines in Fig. 2,) by bearing downwardly upon the outer or power end of the lever the rack-bar 1 will be forced into position, engaging the wall 2 and under the base-board 4, as hereinbefore described, and when the cam-brace device is brought to the normal position shown in Figs. 1 and 2 it will operate to firmly retain the rack-bar in upright position.

It will be noted that the member 16 when in normal position need project no farther or but little farther than the degree of projection of the shelves 28, whereby compactness in space occupied is secured, and our improved adjustable, attachable, detachable, and portable shelf-supporting device need occupy no greater space than that required for ordinary permanent shelving which is built up and fixed to the wall in permanent attachment by nails or screws or other permanent securing means.

The shelves 28 are supported upon the top surface 12 of the members 9 in number and arrangement as desired, and if it is required that the shelves be secured to the members 9 this may be done by screws, as at 29, or other suitable securing means, for which purpose the top portion 12 of the members 9 may be provided with openings, as at 30.

The operation and advantages of our invention will be readily understood.

Any desired number of main members or rack-bars 1 and any desired number of shelf-supporting members 9 may be employed, according to the length of the shelving and the number of shelves desired. After the members 1, 9, and 16 are mounted in normal position, as shown in Figs. 1 and 2, and the shelving applied the entire device will firmly and securely retain its normal operative position; but by simple operation of the cam-brace device 16 the main members or rack-bars 1 will be released from normal position, and the entire device, with the shelving, can be quickly and readily removed in case of emergency, such as fire, or as desired.

Having thus described our invention, we claim and desire to secure by Letters Patent—

1. An improved shelf-supporting bracket of the class described, comprising main bars adapted to occupy an upright position with relation to a wall or surface and having bearing means engaging said surface, adjustable shelf-supporting members slidable upon said bars, means for retaining said shelf-supporting members in fixed position, and lever-braces having a bearing operation upon said bars at the lower portion thereof, said braces having locking means adapted to engage the floor, substantially as and for the purpose set forth.

2. An improved shelf-supporting bracket of the class described, comprising main bars adapted to occupy an upright position with relation to a wall or surface said bars having bearing means engaging said surface and having a rack at their front edges, shelf-supporting members each pivotally carried upon a slidable sleeve embracing one of said bars, said shelf-supporting members each having a rack edge engaging the rack edge of one of the bars, and lever-braces each pivotally carried upon a sleeve slidably mounted upon one of the bars and each embodying a cam engaging the rack edge of one of the bars and locking means adapted to engage the floor, substantially as and for the purpose set forth.

3. An improved shelf-supporting bracket of the class described, comprising main bars adapted to occupy an upright position with relation to a wall or surface and having projecting extensions at their rear edges adapted to engage said surface and having a rack at their front edges, shelf-supporting members each embodying a sleeve slidable upon one of said bars and a body portion pivoted to said sleeve and having a rack at its inner edge, and lever-braces each embodying a sleeve slidable upon one of said bars, a gravity-cam pivotally carried by said sleeve and having a rack edge, and a lever pivoted to said sleeve and carrying a pivoted fulcrum-bar adapted to engage the floor, substantially as and for the purpose set forth.

4. An improved shelf-supporting bracket of the class described, comprising a main bar adapted to occupy an upright position with relation to a wall or surface, an adjustable brace for forcing said bar to a bearing contact or engagement with said surface, and shelf-supporting members carried by said bar, substantially as and for the purpose set forth.
5. An improved shelf-supporting bracket of the class described, comprising a main bar adapted to occupy an upright position with relation to a wall or surface, an adjustable brace for forcing said bar to a bearing contact or engagement with said surface, said brace having locking means adapted to bear against the floor, and shelf-supporting members carried by said bar above the brace, substantially as and for the purpose set forth.
6. An improved shelf-supporting bracket of the class described, comprising a main bar adapted to occupy an upright position with relation to a wall or surface and having shelf-supporting means and a rack at its front edge; and a brace embodying a member slidable upon said bar, a cam pivotally carried by said slidable member and having a rack edge, a lever pivoted to said slidable member, and a fulcrum-bar pivoted to the lever and adapted to engage the floor, substantially as and for the purpose set forth.
7. An improved shelf-supporting bracket of the class described, comprising a main bar adapted to occupy an upright position with relation to a wall or surface and having a 35 rack at its front edge; shelf-supporting members embodying a member slidable upon said bar, and a member having right-angular surfaces one of which forms an engaging rack, said member being pivotally connected to 40 said slidable member at the vertex of the angle formed by said surfaces; and means for forcing and retaining said main bar to a bearing contact or engagement with the wall or surface; substantially as and for the purpose 45 set forth.
8. An improved shelf-supporting bracket of the class described, comprising a main bar adapted to occupy an upright position with relation to a wall or surface and having 50 means for maintaining a bearing contact or engagement with said surface, an adjustable brace device having means for a bearing contact or engagement with the floor and bearing against said main bar to force and maintain the same in bearing contact or engagement with the wall or surface, and adjustable shelf-supporting means carried by said bar, substantially as and for the purpose set forth.

In testimony whereof we have signed our names in the presence of the subscribing witnesses.

JOSHUA J. WORLEY.
